UNITED STATES PATENT OFFICE.

JOHN H. JOHNSTON, OF NEW YORK, N. Y.

DESIGN FOR A SPOON.

SPECIFICATION forming part of Design No. 20,494, dated February 3, 1891.

Application filed December 29, 1890. Serial No. 376,131. Term of patent 7 years.

To all whom it may concern:

Be it known that I, JOHN H. JOHNSTON, a citizen of the United States, residing at New York city, State of New York, have invented 5 a certain new and ornamental Design for Spoons, of which the following is a description.

The design is represented in the accompanying drawing, which shows a spoon having a conventional bowl and stem or handle extending from it. On the end of the handle is a statuette representation of Peter Stuyvesant, the last Dutch director-general of New Netherland. The figure constitutes a 15 prolongation of the stem or handle of the spoon and represents the doughty governor of New York standing erect. One leg from the knee down is provided with the familiar wooden stump, and otherwise the figure is in 20 detail in accordance with the usual representations well known to all. The head is hatless and is quite bald at the top, the hair at the sides being long and falling on the collar, and the coat short and square like a sack-coat. 25 A sword is suspended at the left side from a strap crossing the right shoulder and the left hand grasps the hilt of the weapon. The right hand leans upon the head of a cane. The lowerlimbs are clad in knee-breeches, and

the single calf is incased in a stocking. On 30 the end of the handle a foliated tuft forms the base on which the figure stands. On the handle of the spoon below the figure are the words "New York," in raised ornamental letters, the words being read with the handle of 35 the spoon held vertically. These letters are inconspicuous and are not of the essence of the design.

In the drawing, A represents the bowl of the spoon; B, the slender stem extending 40 therefrom; C, the figure of Peter Stuyvesant, and at D the words "New York" are seen.

It is thought unnecessary to further letter the design, as its general appearance and detail are obvious from the accompanying 45 drawing.

I claim as my invention and desire to secure by Letters Patent—

The design for spoons herein described and illustrated.

In witness whereof I have hereunto signed my name in the presence of two subscribing witnesses.

JOHN H. JOHNSTON.
